UNITED STATES PATENT OFFICE.

ALLEN C. ALLAN, OF CHICAGO, ILLINOIS.

WRENCH.

1,386,149.

Specification of Letters Patent.

Patented Aug. 2, 1921.

Application filed April 26, 1920. Serial No. 376,568.

To all whom it may concern:

Be it known that I, ALLEN C. ALLAN, a citizen of the United States, residing at Chicago, in the county of Cook and State 5 of Illinois, have invented certain new and useful Improvements in Wrenches, of which the following is a specification.

My invention relates to tools such as wrenches, pliers, and the like, and concerns 10 more particularly their features and elements of construction relating to their fulcrum mountings with reference to one another and the means for controlling and effecting the action of the work-gripping 15 jaws.

The leading aim and purpose of the invention is the provision of a tool of this general character which may be quickly and accurately applied to the body to be grasped, 20 which holds to such body firmly and securely, which is simple in construction, which is composed of but few parts, which is economical to manufacture, which is easily operated even by novices, and which is 25 unlikely to become damaged or injured in service.

To enable those skilled in this art to have a full and complete understanding of the improved tool, I have illustrated an embodiment of the same in the accompanying drawing forming a part of this specification, to which reference should be had in connection with the following detailed description, and throughout the several views 35 of which like reference characters refer to the same parts.

In this drawing:

Figure 1 is a face view of a desirable incorporation of the invention in physical 40 form showing the jaws of the tool part way open;

Fig. 2 is an edge view of the appliance;

Fig. 3 is an opposite edge view of the same; and

Fig. 4 is an enlarged cross-section on line 4-4 of Fig. 1.

Referring to the drawing, it will be readily seen that the tool of Figs. 1 to 3 inclusive comprises a handle-element 9 with a 50 suitable, curved handle-portion 10, such element being equipped at its other end with a laterally-extended work-engaging jaw 11, having, if desired, a roughened or toothed face 12. The element 9 also has an intermediate part 13 of reduced thickness forming on one face of the member a transverse,

diagonally-disposed or oblique groove with end walls 14 and 15, the thickness of such part 13 being practically one-half that of the jaw or handle element. 60

Coöperating with such member is a second or complementary, reversely-curved handle-element 16 having at one end a jaw 17, the full thickness of the member and desirably roughened or toothed on its end at 65 18, a handle-portion proper 19 at the other end, and an intervening or intermediate section 20 of substantially-half thickness occupying and slidable in the groove of the other member. 70

The part 13 has a stud, pin, bolt, or the like 21 projecting through a curved slot 22 in the thinner or overlying portion 20 of the second handle-element 16, the slot being a length to prevent the element 16 from being 75 slid far enough to the left, as the parts are viewed in Fig. 1, to permit the jaw-head 17 to overlap the end of jaw 11, which, if allowed, would prevent the quick and effective grasp of the jaws on the body to be held between them. In other words, the length of the slot is such as to eliminate the possibility of the relatively-slidable jaws becoming undesirably interlocked or associated together. 80

The parts of the tool are so shaped, 85 formed, and combined that, when the handle portions 10 and 19 are squeezed or pressed together to grasp a body, such as a nut, between the jaw-faces 12 and 18, the lower edge of the section 20 of the second handle-element 16 bears on the corresponding end wall 15 of the groove 13 at 23 near the edge of the part 13 remote from the handle-portion 19, the edge of jaw 18 presses against the adjacent edge face of the member 9, and the wall of slot 22 may or may not bear on the pin or stud 21, although it is usually desirable that it should for a suitable distribution of the strains incident to the operation of the tool. 95 100

By reason of the sliding connection between the two elements of the tool, its jaws may be quickly adjusted to the body to be grasped thereby, and, because of the several sliding bearings between the two members 105 positioned and related as shown, an effective and efficient lever arrangement is secured for holding the body between the jaws with the expenditure of a relatively small amount of effort on the part of the 110 operator. Also the wrench may be readily and quickly adjusted with one hand to dif-

ferent dimensions between the jaws ready for coöperation with nuts or other bodies of different sizes.

By having the lever or member 20 bear on the end-wall of the groove a substantial portion of the strain which would otherwise be on the pin or stud 21 may be removed therefrom, and to assist in further eliminating the strain on the stud or its retaining nut, the edge portion 24 of the member 20 is beveled or chamfered to correspond to a similar slanting undercut 25 on the active section of the end wall 15, whereby such overlapping of the parts tends to hold the two elements flatwise against one another without modifying their capacity for sliding and rocking on one another.

The embodiment of this invention illustrated and described in detail is merely by way of example only since the invention is susceptible of a variety of embodiments all differing from one another more or less in mechanical details, but all incorporating the same fundamental principles of construction and modes of operation. These devices may, therefore, be changed without departure from the substance and essence of the invention and without the sacrifice of any of its substantial and practical benefits and advantages.

I claim:

1. In a wrench of the character described, the combination of a first handle-member having a transverse groove between its ends and bent laterally at one end to provide a first jaw, a second handle-member crossing said first handle-member, occupying said groove, and having a second jaw at one end adapted to coöperate with said first jaw, and a pin and slot connection between the overlapped parts of said members, the second jaw bearing on an edge of said first handle-member and an edge of the second handle-member simultaneously bearing on the end wall of the groove remote from the jaws and adjacent to that edge of the first handle-member on which the second jaw bears for all positions of the jaws within the

capacity of the tool and with the active jaw faces substantially parallel.

2. In a wrench of the character described, the combination of a first handle-member having a transverse groove between its ends and bent laterally at one end to provide a first jaw, a second handle-member crossing said first handle-member, occupying said groove, and having a second jaw at one end adapted to coöperate with said first jaw, and a pin and slot connection between the overlapped parts of said members, the second jaw bearing on an edge of said first handle-member and an edge of the second handle-member simultaneously bearing on the end wall of the groove remote from the jaws and adjacent to that edge of the first handle-member on which the second jaw bears for all positions of the jaws within the capacity of the tool and with their active jaw faces substantially parallel, said slot being of such length as to prevent the second jaw from overlapping the end of the first jaw.

3. In a wrench of the character described, the combination of a first handle-member having a transverse groove between its ends with an undercut end wall and bent laterally at one end to provide a first jaw, a second handle-member crossing said first handle-member, occupying said groove, and having a second jaw at one end adapted to coöperate with said first jaw, and a pin and slot connection between the overlapped parts of said members, the second jaw bearing on an edge of said first handle-member and an edge of the second handle-member simultaneously bearing on and underlying the undercut in the wall of the groove remote from the jaws and adjacent to that edge of the first handle-member on which the second jaw bears for all positions of the jaws within the capacity of the tool and with their active jaw faces substantially parallel, said slot being of such length as to prevent the second jaw from overlapping the end of the first jaw.

ALLEN C. ALLAN.
